UNITED STATES PATENT OFFICE.

JOSEPH W. SAVERY, OF SAN FRANCISCO, CALIFORNIA.

SMOKER'S STAND.

Application filed August 23, 1926. Serial No. 131,044.

This invention relates to improvements in "smoker's stand" of the class having a base with a hollow tube connecting the base to a tray for the deposit of cigar and cigarette ashes, butts, and other waste, as burnt matches, etc.

The object of the present invention is to provide more convenient means for emptying and cleaning the stand. One of the means to that end is the provision of a base with a hinged cover member on which is a taper hollow tube. Another means to attain that object provides for a removable waste receptacle in the base of the stand. Other objects will appear to those skilled in the art as the description proceeds.

An embodiment of the invention is shown in the accompanying drawing, in which the same reference numeral is applied to the same portion throughout, but I am aware that modifications may be made in the construction shown.

Figure 1 is a side elevation of the complete stand.

Figure 2 is a rear elevation of the stand showing the hinge.

Figure 3 is a plan of the stand.

Figure 4 is an enlarged view of the base, the hinged cover, and part of the tube, in section, showing the removable waste receptacle therein.

Figure 5 is a detached view of the removable waste receptacle.

The numeral 3 represents the base to which a cover is attached by a hinge and is held in the closed position by the pin 4 which is fixed to a spring 5 attached to the base by rivets or other means. The pin 4 is adapted to snap into a hole 6 in the cover.

On the inside of the base is a lining 7 of sheet metal spaced from the bottom and held at the edges by the seam 8. The space thus formed is adapted to be filled with some heavy material like lead 9 to obtain the required ballast.

The base is partly spherical in form in this instance, and has the flat central portion 10, grooves 11, and the rounded up sides 12. The flat portion extends from A to B. The

base has a cover 13 which is hinged to the base by means of the hinge 14 which may be attached by the rivets 15 or other means. The cover is partly spherical and has the large end of a taper tube 16 fixed in a central opening therein.

The tube is long enough to make a convenient smoker's stand, and has the tray 17 fixed on the upper end. The tray has a flat place 18 and has an opening in the center, opening into the tube. A match box holder 19 of well known type is fixed on the tray.

The taper tube may be of any shape in cross section, a hexagon is shown, but a round, square, oval or other shape may be used.

Fitting into the base and conforming to the shape of the bottom thereof is a waste receptacle 20 which is adapted to be taken out and emptied when filled. The receptacle has the turned over rim 21.

In use, ashes, cigar stubs, etc., are dropped into the tray where it falls down the tube to the waste receptacle. To remove the receptacle the pin 4 is pressed in, to release the cover which is tilted back on the hinge, the waste receptacle taken out, emptied, and cleaned. The interior of the base, cover, and tube can be more readily cleaned by means of this invention.

The stand is preferably made of sheet metal but may be made of other material.

What I claim is as follows, but various modifications may be made in the construction shown in the drawings and above particularly described form within the scope of the claims.

A smoker's stand of the class described comprising a partly spherical base, a partly spherical cover hinged to open radially on said base, a taper tube fixed to said cover, a tray on said tube, and a waste receptacle in said base adapted to extend above the meeting line of said base and said cover.

In testimony whereof I have hereunto set my hand this 17th day of August, A. D. 1926.

JOSEPH W. SAVERY.
